UNITED STATES PATENT OFFICE.

LUDWIG BERANEK AND JOSEPH BERANEK, OF CHICAGO, ILLINOIS.

WINDOW-SEAT.

1,252,386.

Specification of Letters Patent.

Patented Jan. 8, 1918.

Application filed April 20, 1916. Serial No. 92,410.

To all whom it may concern:

Be it known that we, LUDWIG BERANEK and JOSEPH BERANEK, citizens of the United States, and residents of the city of Chicago, 5 county of Cook, and State of Illinois, have invented certain new and useful Improvements in Window-Seats, of which the following is a specification.

Our invention relates to improvements in 10 window seats which are designed for use in connection with windows to facilitate washing of the outer sides of the windows and to render this work safe.

The object of our invention is the production of a window seat which will be of durable and economical construction, one which may be readily and easily arranged in place or removed, and one which, when not in use, may be folded into compact form.

20 Other objects will appear hereinafter.

The invention consists in the combinations and arrangements of parts hereinafter described and claimed.

The invention will be best understood by 25 reference to the accompanying drawings forming a part of this specification, and in which,

Figure 1 is a top plan view of a window seat embodying the invention,

30 Fig. 2 is a side elevation of the window seat showing the same applied to a window sill, the latter being shown in dotted lines,

Fig. 3 is an enlarged vertical transverse section through the body of the seat,

35 Fig. 4 is a section taken on line $x-x$ of Fig. 3, and

Fig. 5 is a rear elevation of the back rest of the seat.

The preferred form of construction as 40 illustrated in the drawings, comprises a rectangular body or seat-forming portion proper 1. Coöperating with the body 1 is a back rest 2 which is swingingly or foldably connected with the rearward edge of the said

45 body as at 3. Coöperating with said back rest are foldable brace rods 4, the same being provided intermediate their ends with joints 5 whereby said brace rods may be collapsed or folded upon themselves to per-

50 mit of the back rest being folded to position on the upper side of body 1 when the device is not in use. Thus it will be seen that when the device is in folded position the same will occupy very little space for storage or trans-

55 portation. The back rest 2 is reinforced at its rearward side by the extension of the

hinge leaves upwardly thereon adjacent the lateral edges of said back rest, and by means of a transversely extending strap 6 provided at the rearward side thereof as clearly shown 60 in Fig. 5.

The body 1 is reinforced by two straps or elongated metallic plates 7 which are secured at the under side thereof adjacent the lateral edges of said body. Coöperating 65 with said body for connection of the same with the sill of the window in connection with which the same is employed, are two hook members 8 the forward ends of which are formed as seen, to adapt the same for 70 embracing of the inner edge of the inner sill of a conventional window. The rearward ends of hook members 8 slidably engage in elongated sockets formed in the body 1 by elongated shallow grooves 9 which are provided in the upper side of said body, said grooves being covered by elongated metallic plates 10. Said hook members are locked in positions of sliding adjustment by means of bolts 11 which are adapted to project 75 through alining openings which are formed in the forwardly extended end portions of the plates 7 and 10, the rearward ends of said hook members being formed with spaced openings 12 which are adapted for 80 registration with the openings in members 7 and 8. When the bolts 11 are engaged with said openings, as shown in Fig. 3 it is of course apparent that the hook members 8 are securely locked against sliding movement. Thumb nuts 13 coöperate with bolts 11. The adjustable fastening of the hook members 8 of course permits of adjustment of the same to engage with window sills of 85 various widths or sizes, thus extending the 90 field of usefulness of the device. To prevent marring of the inner window sill engaged by the device sleeves 14 of felt or other suitable material are provided upon the forward ends of hook members 8 and adjacent portions of the plates 7 and 10.

Arranged upon the underside of the body 1 is a supporting element adapted for engagement with the upper side of the outer sill of the window when the device is in use. 105 Said supporting element comprises a pair of spaced blocks 15 which are rigidly connected by a cross piece 16. Said supporting element is connected with the member 1 by means of straps 17 provided upon the outer 110 sides of blocks 15, the upper ends of said straps being formed into laterally project-

ing slotted lugs 18 adapted for engagement with studs 19 or 19' which project downwardly from body 1. Thumb nuts 20 coöperate with said studs in fastening the supporting element thereto. Two sets of studs 19 and 19' are provided in order to allow for adjustment of the supporting element so as to permit of use of the device upon the windows of frame as well as brick buildings, it 10 being of course understood that the width of the sills of these two classes of buildings vary. To prevent marring of the outer sill of the window the seat is provided at its underside with buffers 22 of rubber or other 15 suitable material. Said buffers also serving to prevent sliding or relative shifting of the device when in use.

By the construction as set forth it will be seen that when in use, the same will be 20 locked against relative outward movement through engagement of the hook members 8 with the inner edge of the inner window sill. Shoulders 23 and 24 engaging against the off-set portions or shoulders of the conventional window sill will serve to lock the 25 device against relative inward movement. Thus it will be seen that the device will be securely fastened to the window frame, the back rest and brace rods coöoperating there- 30 with serving to prevent the occupant of the seat from falling therefrom. The device is of light though strong and durable construction, the same may be collapsed into a very small space, when not in use, and may be 35 readily and expeditiously arranged in operative relation with a window or as quickly and easily removed therefrom when desired. While we have illustrated and described 40 the preferred form of construction for carrying our invention into effect, this is capable of variation and modification without departing from the spirit of the invention.

We, therefore, do not wish to be limited to the precise details of construction set forth, but desire to avail ourselves of such variations and modifications as come within the scope of the appended claim. 45

Having described our invention what we claim as new and desire to secure by Letters Patent is:

A window seat comprising a body; means on said body for engagement with a window sill to secure the same thereto, said means comprising a pair of hook members mounted on said body for sliding adjustment to 55 embrace the inner edge of a window sill; elongated sockets in said body in which the rearward ends of said hook members are slidably mounted, each of said sockets being formed of a shallow groove provided in the upper side of said body; a plate covering the upper side of said groove and extending forwardly beyond the forward edge of said body; a second plate secured to said body and extending forwardly from the forward edge thereof below and spaced from said forward end portion of said first mentioned plate; said forward end portions of said plates having alining openings and the rearward end portions of said hook members having spaced openings adapted for registration with said first mentioned openings; and means adapted for engagement with said openings to lock said hook members in positions of sliding adjustment, substantially as described. 60

In testimony whereof we have signed our names to this specification in the presence of two subscribing witnesses.

LUDWIG BERANEK.
JOSEPH BERANEK.
